UNITED STATES PATENT OFFICE.

DAVID P. PERRY, OF CHICAGO, ILLINOIS, ASSIGNOR, BY MESNE ASSIGNMENTS, OF TWO-THIRDS TO WILLIAM MORRISON, OF CHICAGO, ILLINOIS, AND ONE-THIRD TO M. A. LUMBARD, OF DES MOINES, IOWA.

STORAGE BATTERY.

942,279.

Specification of Letters Patent.

Patented Dec. 7, 1909.

Application filed October 12, 1903. Serial No. 176,802.

To all whom it may concern:

Be it known that I, DAVID P. PERRY, a citizen of the United States of America, and resident of Chicago, Cook county, Illinois, 5 have invented a certain new and useful Improvement in Storage Batteries, of which the following is a specification.

My invention contemplates an improved and highly efficient form of storage battery.

10 In a storage battery embodying the principles of my invention, the positive pole electrode or element consists preferably of a horizontally disposed perforated copper tube filled with any suitable material, as, for example, oxids of nickel and silver. Upon this perforated tube is preferably fitted a perforated tube of rubber or other suitable insulation, and between the copper and rubber tubes there may be interposed one or 15 more layers of paper and linen or other suitable material. The negative pole electrode preferably consists of a cylinder of wire cloth, as, for example, a cylindric copper wire screen, and this reticulated copper 20 wire cylinder is arranged outside of and concentric with the positive pole electrode. Rings of rubber or other similar material can be employed for centering the positive pole electrode within the negative pole electrode, and for maintaining an equality of 25 distance between all points on the outer surface of the positive pole electrode and the inner surface of the negative pole electrode; the difference in diameter of the two elec- 30 trodes or elements being sufficient to provide the desired space, say, one-fourth of an inch, between the outer surface of the positive pole electrode and the inner surface of the negative pole electrode. Rubber disks 35 can be employed to close the ends of the cylindric and tubular positive and negative pole electrodes, these disks being preferably so applied that they assist in maintaining the concentricity of the two cylindric ele- 40 ments. The cell can be of metal, thus constituting the negative pole of the battery, while an insulated rod or bolt extends from the positive pole electrode and constitutes the positive pole of the battery. Any suitable 45 electrolyte can be employed. For example, zincate of potash, or any other suitable alkaline zincate, can be employed as the electrolyte, a sufficient quantity of this solution being preferably provided to permit the

horizontally disposed and concentric positive and negative pole electrodes to be completely submerged below the surface of the electrolyte. In the charge, zinc is deposited upon the wire cloth or screen, and in the discharge there is a dissolution of the zinc thus 55 electrolytically deposited on the wire screen, the zinc returning to the solution in the ordinary and well-known manner.

The horizontal arrangement of the two elements, and the concentric arrangement of 60 one cylindric element within the other, are of very great importance and cause an exceedingly efficient and satisfactory action. The work or generation of current is evenly 65 distributed along the entire length of the negative pole electrode, as the opposing surfaces of the two elements extend horizontally and, therefore, at right angles to the direction of the force of gravity. Being thus arranged, the elements and the efficiency 70 of the battery will not suffer materially from the effects of specific gravity—that is to say, from the tendency of an electrolyte to resolve itself into strata. Furthermore, 75 it will be seen that all points on the negative pole electrode are equally distant from the axis of the positive pole electrode, and are an equal distance from corresponding points on the cylindric outer surface of the positive pole electrode.

80 The nature and advantages of my invention will, however, hereinafter more fully appear.

In the accompanying drawings: Figure 1 is a vertical longitudinal section through a 85 storage battery embodying the principles of my invention. Fig. 2 is a horizontal section on line 2—2 in Fig. 1. Fig. 3 is a transverse section on line 3—3 in Fig. 1. Fig. 4 is a transverse section on line 4—4 in Fig. 1. Fig. 5 is a perspective, broken at the center 90 for convenience of illustration, of the negative pole electrode in a partially unrolled condition. Fig. 6 is a perspective of the 95 perforated copper and rubber tubes which constitute the positive pole electrode, showing the rubber rings and end pieces in place. Fig. 7 is a perspective of the perforated rubber tube. Fig. 8 is a perspective of a rubber 100 block which is placed upon the positive pole. Fig. 105

As thus illustrated, my improved storage battery comprises a cell A, of copper or any other suitable material, a positive pole elec-

trode B, and a negative pole electrode C. The said cell, as illustrated, is box-like in form and is provided with a neck a having its upper end provided with a perforated 5 rubber diaphragm a^1 and a threaded cap a^2 . The said cap holds the said perforated diaphragm in place and both can be removed in order to obtain access to the interior of the cell. The positive pole electrode B consists preferably of a perforated copper tube. 10 The working of the battery can be greatly improved by placing a cylindrical layer or layers of linen b around the said copper tube; by interposing paper b^1 between this 15 linen and the copper tube; and by then fitting upon said layer of linen a perforated rubber tube b^2 , the perforated copper and rubber tubes being fitted tightly together with the interposed layers of linen and paper 20 or other suitable material compressed tightly between them. The positive pole electrode, thus constructed, can be provided internally with a copper conductor or tube b^3 having a screw-threaded socket adapted to receive 25 the lower end of the threaded bolt or rod b^4 , which serves as the positive pole. This bolt or rod extends upwardly through the interior of the battery, is thoroughly insulated by the surrounding portions of insulation b^5 , b^6 , and is provided at its upper 30 portion with a couple of clamping disks b^7 and b^8 adapted to clamp the upper wall of the cell tightly between them. A sheet of rubber b^9 is preferably interposed between 35 the nut b^{10} and the disk b^8 , and a similar sheet of rubber b^{11} is interposed between the disk b^8 and the lower surface of the upper wall of the cell. Preferably, the disk b^8 is provided with a boss b^{12} , which extends upwardly through the upper wall of the cell 40 and through the disk b^7 . A layer of rubber b^{13} is interposed between the washer b^{14} and the opposing surfaces of the disk b^7 and the boss b^{12} . A nut b^{15} is provided for clamping 45 the parts tightly together and for compressing the soft rubber layers to an extent to provide tight joints and preclude all possibility of leakage.

The negative pole electrode C consists, 50 preferably, of a cylinder of wire cloth, as, for example, a cylinder of copper wire gauze rolled up in the manner shown in Fig. 5. At this juncture, it may be stated that the inner edge of this wire fabric is preferably, 55 as shown, so woven into the side wall of the cylinder that the inner surface of the cylinder presents no ridges or exposed wire ends. In other words, in order to insure the best results, the inner surface of the negative 60 pole electrode is preferably smooth and free from projections, ridges, or exposed ends of the wire.

In assembling the different parts, the positive pole electrode is first placed within the 65 negative pole electrode, one or more rubber

rings D being provided for maintaining the proper distance between the two elements, and for maintaining the concentricity of the two elements, which latter is an important feature of my improved battery.

The end disks, having cavities e adapted to receive the ends of the positive pole electrode, and projections e^1 adapted to engage the open ends of the chamber b^3 , are then slipped into the ends of the negative 70 pole electrode, these disks being inserted far enough within the negative pole electrode to permit the ends of the latter to be pressed over and folded down flat upon the outer surfaces of the disks. The provision and application of these end disks plays an important part in the action and working of the battery, as they prevent any tendency toward concentration of the action at and around the ends of the elements. Wire 75 rings F are then applied to the outer surface of the negative pole electrode, and are so located as to bind the said element tightly upon the disks E and the ring or rings D. The bolt or rod b^4 is then inserted through 80 both elements and secured tightly into the copper tube b^3 . In use, the cylindric and self-contained structure thus produced by tightly securing the two elements together is supported at its ends by shoulders G 85 formed at the bottom of the cell. The folded over ends of the negative pole electrode C bear tightly against the end walls of the copper cell. A screen H of wire gauze of copper or other suitable metal is preferably 90 interposed between the negative pole electrode C and the bottom and sides of the copper cell. This screen can be of finer mesh than the negative pole electrode, and thus adapted to catch and prevent the zinc from 95 falling down and accumulating in the corners of the cell. At the same time, this screen H permits the dirt and sediment to 100 pass below.

The positive pole electrode can be filled 110 with oxids of nickel and silver b^5 or with any other suitable, known or approved substance. If nickel and silver are employed, a very satisfactory way of preparing the same is as follows: Take a sufficient quantity of nickel and silver and dissolve the same together in nitric acid. Next, and after the nickel and silver are thoroughly dissolved, add a sufficient quantity of a strong solution of potash or soda, so as to 115 precipitate the nickel and silver as oxids. When thoroughly precipitated, and when the precipitate has been allowed to thoroughly settle, and after the acid, etc., has been poured off, then pour in water and wash the precipitate several times. It must be washed several times in order to get rid of all the acid. After it has been repeatedly washed and allowed to settle, it can then 120 be allowed to dry in any suitable manner, 125 130

and can be further treated and prepared and made ready for placing in the battery. The final product is a dry powder, which is an oxid of silver and nickel, and which 5 is a perfect mixture, owing to the simultaneous precipitation of the two metallic oxides.

The electrolyte can also be of any suitable, known or approved character—for example, an alkaline solution of zinc, such as 10 zincate of potash. Preferably, this solution is employed in sufficient quantity to permit the two concentric elements to be completely submerged below the surface of 15 the electrolyte. And it may be stated, at this juncture, that this total and constant submersion of the two elements below the surface of the electrolyte, the elements being thus completely submerged at all times, 20 constitutes an important and desirable feature of my improved battery. In the charge, the zinc of the solution is deposited upon the reticulated wire screen C, which constitutes the negative pole electrode. In 25 use, and when the battery is discharged, the current is generated at, and passes from, the negative pole electrode C to the positive pole electrode B, causing the zinc to return to the solution. The provision of the linen 30 b, the paper b¹ and the perforated rubber tube b², also constitutes an important feature of my invention, as it protects the surface of the positive pole electrode. The paper and linen prevent the oxids of nickel 35 and silver from becoming dislodged and leaving the perforated copper tube. The perforated rubber tube holds the porous layers in place. The horizontal arrangement of the two elements, together with the 40 concentric arrangement of these elements, and the consequent uniformity of distance between all points on the surface of the positive pole electrode and the inner surface of the negative pole electrode insures a uniform and even distribution of the work or 45 electrical action over the surfaces of the two elements, and particularly upon the surface of the negative pole electrode.

Any gas which is generated in the cell can 50 readily escape through the small opening a³ in the rubber diaphragm a¹.

The arrangement of the concentric and cylindric elements B and C in a horizontal position insures an efficient and satisfactory 55 action. For with a horizontal arrangement, the elements are obviously subject to the same character of electrolyte throughout their lengths. Thus the possibility of injurious effects from differing specific gravities is reduced or minimized. The tube b³, as stated, serves as a conductor to carry off the current. It is admirably adapted for this purpose, as it extends the entire length 60 of the positive pole electrode B, and is firmly embedded in the active material, or ma-

terial to become active, with which the perforated copper tube is filled.

In use, the silver oxid gives the conductivity and furnishes some oxygen, while the nickel oxid furnishes the greater part of 70 the oxygen necessary for a proper working of the battery. And this is all accomplished by the use of an exceedingly cheap and inexpensive article—that is to say, the nickel is much cheaper than other substances which 75 could be employed for the same purpose. Furthermore, nickel oxid and silver oxid are practically of the same character, as far as electrical voltage is concerned, and as the nickel is of a low atomic weight, the use 80 of these two metals in this manner gives exceedingly satisfactory results. In use, the silver oxid is active in giving a certain voltage, and the nickel oxid then follows with practically the same degree of voltage. 85 Thus, in use, the voltage of the battery is practically the same throughout the discharge.

What I claim as my invention is:

1. A storage battery comprising a suitable metallic cell, a horizontal cylindric reticulated negative pole electrode, a cylindric positive pole electrode arranged concentrically within said negative pole electrode, a cylindric conductor arranged concentrically 95 within said positive pole electrode, and a suitable electrolyte.

2. A storage battery comprising a suitable cell, horizontally arranged positive and negative pole electrode, arranged one within 100 the other and suitably mounted within said cell, disks of insulation inserted within the ends of the negative pole electrode and closing the ends of the positive pole electrode, and a suitable electrolyte.

3. A storage battery comprising a suitable cell, horizontally arranged cylindric positive and negative pole electrodes mounted within said cell, the positive pole electrode being arranged concentrically within 110 the negative pole electrode, circular pieces of insulating material for maintaining the concentricity of the two elements, and a suitable electrolyte.

4. A storage battery comprising a metallic cell, a cylindric and horizontally arranged negative pole electrode suitably mounted within said cell and consisting of a cylinder of wire gauze, a cylindric negative element arranged concentrically within said negative pole electrode, said positive pole electrode element comprising a perforated metallic tube filled with suitable active material, there being a layer of porous material applied to the outer surface of said perforated metallic tube, there being a perforated rubber tube fitted upon said layer of porous material, means intermediate the ends of the elements for maintaining the latter in their proper relative positions, 125 130

disks of insulation inserted within the ends of the negative pole electrode and closing the ends of the positive pole electrode element, means for binding the two elements 5 firmly together, an insulated terminal extending from the positive pole electrode, and a suitable electrolyte in which the two elements are completely submerged.

5. A storage battery comprising a cylindric negative pole electrode, a cylindric positive pole electrode of less diameter than the negative pole electrode and arranged concentrically within the latter, a cylindric conductor of less diameter than the positive 10 pole electrode and arranged concentrically within the latter, the said elements being arranged horizontally, a cell containing said elements, a suitable electrolyte, and suitable active material surrounding said conductor 15

and filling the bore of said positive pole 20 electrode.

6. A storage battery comprising a suitable cell, a suitable negative pole electrode, a suitable electrolyte, a cylindric positive pole electrode containing suitably prepared 25 oxids of nickel and silver, and a metallic conductor of less diameter than the positive pole electrode and arranged concentrically within the latter, the said conductor and positive pole electrode being substantially of 30 the same length.

Signed by me at Chicago, Cook county, Illinois, this 29th day of September 1903.

DAVID P. PERRY.
